BARBECUE

Silman H. Aaronson, Brooklyn, N. Y.

Application February 8, 1955, Serial No. 34,407

Term of patent 14 years

(Cl. D81—10)

Fig. 1 is a front perspective view of a barbecue, showing my new design.

Fig. 2 is a front perspective view illustrating the door portion in open position.

The top and rear, and left sides not shown are substantially plain.

I claim:

The ornamental design for a barbecue, substantially as shown and described.
